SINK CONSTRUCTION AND INSTALLATION

Milton D. Skinner, Port Credit, Ontario, Canada

Application August 22, 1947, Serial No. 770,017

5 Claims. (Cl. 4—187)

1

This invention relates to the construction and installation of sinks and like fixtures and the principal object of the invention is to provide a very simple sink installation which can be manufactured at a relatively low cost and which will enable the sink to be quickly and readily installed in position with a flush joint sealing the edge of the surrounding linoleum or other fabric covering for the sink boards and which will ensure a positive water-tight seal between the sink edge and the surrounding linoleum to prevent water from seeping under the edge of the sink thus effectively precluding deterioration and rotting of the linoleum and drain board located beneath the sink edge.

A further and important object is to provide a sink structure which can be cast as an integral unit to include the means to enable the water-tight seal between the sink edge and the surrounding linoleum or overlay to be effected.

A still further object is to provide a sink which can be quickly installed and the sealing edge joint effected without requiring skilled labour or special tools.

The principal feature of the invention consists in providing a sink adapted to seat in an opening in a drain board covered with linoleum or other fabric overlay, the sink having an outwardly flanged upper edge to overlap the surrounding edge of the drain board opening and incorporating means to enable the surrounding edge of the drain board overlay to be clamped to the underside of the sink flange and providing clamping means co-operating with the sink means for securely clamping the overlay in a water-tight seal against the sink flange to prevent the ingress of water beneath the edge of the sink to deteriorate and rot the overlay and drain board.

A further and important feature consists in forming the sink as a cast unit with the incorporated means for co-operating with the overlay clamping means formed as integral bolt-retaining recesses formed in the casting operation.

Referring to the accompanying drawings, Figure 1 is a fragmentary plan view of a sink installation embodying my invention.

Figure 2 is a vertical sectional view taken on the line 2—2 of Figure 1, clearly showing the construction of the sink and the manner in which the drain board overlay is clamped to the underside of the edge thereof.

Figure 3 is a perspective view of a portion of the underside of the sink flange with a portion of the sink broken away to clearly illustrate the bolt-retaining recesses.

2

Figure 4 is a perspective view of one of my clamps used in obtaining my water-tight joint.

In the past a great deal of difficulty has been experienced in forming and maintaining a water-tight joint between the rim of a sink and the linoleum or fabric overlay covering the supporting drain board in which the sink is mounted.

The necessity of having a water-tight edge seal or joint has long been realized as the ingress of moisture beneath the edge of the sink leads to rotting of the overlay and supporting wood frame. In extreme cases a poor joint will permit the water from the drain board to spill onto the flooring beneath the sink.

15 The present invention has been devised to overcome the above difficulty by ensuring that a water-tight seal or joint is effected between the drain board overlay and the sink edge.

With reference to the accompanying drawings, 20 I show a drain board generally designated at 1, which is formed of suitable sheeting 2. The drain board is formed with an opening 3 adapted to receive a sink or basin 4.

25 The edge of the drain board opening 3 is bevelled inwardly and downwardly as at 5 and arranged on the upper surface of the drain board is an overlay fabric 6, such as linoleum or other suitable fabric or material.

30 The overlay fabric 6 is arranged to extend over and inwardly of the drain board opening 3 to provide an overhanging edge strip 7 extending around the opening 3. A suitable piece of moulding or trim 8 may be utilized to secure the outer edge of the overlay to the drain board.

35 The sink or basin 4, which is preferably an integral cast unit, is formed with an outwardly extending rim or flange 9, the underside of which is bevelled at 10 corresponding to the bevel 5 of the edge of the drain board opening 3.

40 Arranged at intervals on the underside of the sink flange 9 are angle projections 11 which have a leg portion 12 extending down the side wall 13 of the sink. Each of the projections 11 is slotted as at 14 to define two spaced lugs 15 adapted to receive therebetween the shank of the bolt 16, and arranged in the flange above the defined lugs 15 is a recess 17 which is of sufficient width to just receive the head of the bolt 16 and which extends forwardly or outwardly of the ends 18 of the lug to permit the bolt head to be inserted.

45 It will thus be seen that the slot 14 and the recess 17 form a substantially T-shaped slot in the underside of the sink flange to receive and 50 retain the bolt 16.

Arranged on the underside of the sink flange or rim 9 is a ring 19 which extends around the sink and is adapted to be forced towards the sink flange to clamp the edge strip 7 of the drain board overlay to the bevelled underside 10 of the sink flange.

To enable this clamping ring 19 to be forced into clamping engagement with the overlay, clamping means in the form of plates 20 and the bolts 16 are provided. These plates 20 are formed with an orifice 21 to receive the shank of the bolts 16 and are provided with an upturned edge 22.

In utilizing the clamping plates 20 the plates are pushed on to the bolts 16 with the one edge contacting the bottom 23 of the leg portion 12 of the angled projection 11 and with the upturned edge 22 contacting the clamping ring 19, the nut 24 serves to tighten the clamping plates into clamping arrangement about the fulcrum provided by the bottom 23 of the projections 11.

It will thus be seen that in installing my sink the bolts 16 are first inserted into the T-shaped slots as formed by the recesses 17 and slots 14 and the sink inserted into the opening 3 provided in the drainboard with the bevelled underside 10 of the sink rim or flange 9 being supported on the corresponding bevelled edge 5 of the opening 1 with the linoleum or overlay 6 held between the sink flange and edge of the drain board with the edge strip 7, which extends inwardly of the opening 3, engaging the underside of the sink rim.

It will be appreciated of course that the arrangement of the bevelled surfaces 5 and 10 will permit a flush joint to be effected between the sink and drain board.

Next, the clamping ring 19 is placed in position around the sink.

The clamping plates 20 are then pushed on the bolts in position with the one edge contacting the bottom 23 of the sink projection leg 12 and with the upturned edge engaging the clamping ring. The nuts 24 are then threaded on the bolts to urge the edge 22 of the plates 20 into forceful engagement with ring 19 to effect a very secure and water-tight joint between the underside of the sink flange and the overlay.

It will be appreciated that the clamping effect of the plates 20 is greatly enhanced by providing the fulcrum arrangement as formed by the leg 12 of the sink projection.

It has been found in actual practice that it is advantageous to support the underside of the edge strips 7 of the linoleum or overlay to prevent the clamping ring 19 or the edge of the opening 3 from rupturing the overlay material.

I have shown this reinforcing of the underside of the fabric edge strip 7 accomplished by the use of a ring 25 of relatively thin metal interposed between the clamping ring 19 and the edge of the overlay and extending over the edge of the opening 3 in the drain board.

It will be readily appreciated that my sink may be cast as an integral unit with the projections 11 formed in the casting operation to provide a relatively inexpensive sink structure.

It will also be readily appreciated that the drain board may be quickly erected and the linoleum or overlay placed in position and the sink installed, requiring the minimum of labour and time.

Not only is the installation of the sink exceedingly simple, requiring neither skilled labour nor special tools, but the joint effected between the sink and the drain board overlay will be ex-

tremely effective to preclude the possibility of water seeping beneath the sink rim or flange.

In forming the recesses 17 it will be understood that the recesses are of sufficient width to just receive the bolt head and the bolt will be prevented from freely turning in the recess to permit the nut 24 to be tightened.

In the event that the joint beneath the sink and the overlay becomes impaired due to shrinkage of the overlay material, it is merely necessary to tighten the clamping plates 20 to renew the water-tight seal.

While I have shown one particular arrangement for effecting the clamping of the linoleum or overlay to the underside of the sink flange, it will be appreciated that other forms of clamping arrangements may be utilized without departing from the scope of my invention.

What I claim as my invention is:

1. A sink installation comprising a drain surface having an opening formed therein to receive a sink, an overlay material covering said drain surface and projecting inwardly beyond the edge of said drain surface opening, a sink inserted in said opening and having an outwardly extending rim extending over the edge of said opening and engaging over said overlay material, a clamping ring arranged beneath said rim and overlay material for compressing the portion of the overlay material projecting inwardly beyond the edge of said opening against the underside of the sink rim and urging the edge of said rim into said overlay material to provide a water-tight seal around the rim, and means carried by said sink to enable said clamping ring to be applied and maintained in clamping relation.

2. A sink installation comprising a drain board having an opening formed therein to receive a sink, an overlay of compressible material covering said drain board and projecting inwardly beyond the edge of said opening, a sink inserted in said opening and having an outwardly extending rim bevelled to a thin edge and supported by the edge of said opening and engaging over said overlay material, a clamping ring for compressing and clamping the portion of the overlay material projecting inwardly beyond the edge of the drain board opening against the underside of the sink rim, and clamping means supported solely by said sink for urging said clamping ring into clamping engagement with said overlay material and urging the edge of said bevelled rim into said compressible overlay material to provide a water-tight seal at the rim edge.

3. A device as claimed in claim 2 in which the edge of said drain board opening is bevelled to correspond to the bevel of said sink rim to provide a flush joint between said sink and said drain board the weight of said sink holding said sink in supported relation on said drain board with said bevelled edges in juxtaposition, said sink being attached solely to said compressible overlay material.

4. A sink installation comprising a drain board having an opening formed therein to receive a sink and having the upper edge of said opening bevelled, a compressible overlay material covering said drain board and projecting inwardly beyond the edge of said opening, a sink inserted in said opening having an outwardly extending rim bevelled corresponding to the said bevelled drain board edge to a thin edge and engaging over said overlay material, a clamping ring surrounding the underside of said sink rim and engaging the underside of the free unsupported portion of

said overlay material extending beyond the edge of said drain board opening, means supported solely by said sink for actuating said clamping ring to compress said free unsupported portion of the overlay material against said sink rim and for urging the thin edge of said sink rim in a direction to penetrate into the surface of said overlay material to provide a liquid-tight seal around the sink rim.

5. A sink installation providing a water-tight seal around the sink rim and requiring preforming of a drain board only to the extent of cutting an opening therein to receive the sink, comprising in combination a drain board having an opening therein, a sink having an outwardly extending rim to engage over the edge of said drain board opening, a compressible overlay material having an opening to receive the sink and smaller than said drain board opening to define an unsupported overlay portion around the perimeter of said latter opening projecting within said drain board opening when said sink is inserted in said drain board opening with said overlay material overlying said drain board, a clamping ring ar-

ranged beneath said sink rim and unsupported overlay portion, and means supported solely by said sink for actuating said clamping ring into clamping engagement with said sink rim to urge said unsupported overlay portion against the underside of said sink rim to provide a liquid-tight seal between said overlay material and said sink rim around the edge thereof.
